UNITED STATES PATENT OFFICE.

JOHN G. STATTER, OF WILMSLOW, ENGLAND, ASSIGNOR TO WILLIAM MAXWELL SCOTT, OF RADNOR, PENNSYLVANIA.

TIME-ELEMENT DEVICE.

1,100,789.

Specification of Letters Patent. Patented June 23, 1914.

Application filed July 14, 1913. Serial No. 778,861.

To all whom it may concern:

Be it known that I, JOHN G. STATTER, a subject of the King of Great Britain, residing in Wilmslow, England, have invented 5 certain new and useful Improvements in Time-Element Devices, of which the following is a specification.

My invention relates to start delaying or time element devices of the sucker type described in Letters Patent of the United States Number 830,537 granted to me September 11, 1906.

My improved start delaying or time element device is applicable to the tripping 15 mechanism of electric circuit breakers and the like, or in general to any device.

My invention resides in a start delaying or time element device in which the sucker elements are separated or propped apart by 20 small distances whereby a time adjustment is obtained, that is, whereby the duration of time during which the start of a device is delayed may be adjusted or varied.

The greater the distance by which the 25 sucker faces are separated or propped apart the shorter is the time taken to separate the sucker elements with a given force. These distances are extremely small and there is considerable mechanical difficulty in providing 30 suitable means for maintaining the sucker faces apart by the correct amount. And my invention comprises also means for satisfactorily arranging the desired separation and controlling the amount of separation.

My invention resides in the features hereinafter described and claimed.

For an illustration of some of the many forms my invention may take reference is 40 to be had to the accompanying drawing, in which:

Figure 1 is a vertical sectional view, some parts in elevation, through one form of my improved device. Fig. 2 is a vertical sectional view, some parts in elevation, through 45 a modified form of my improved device.

While in the drawings I have shown the sucker elements B and C, Fig. 1, and B and G, Fig. 2, as conical in form, it is to be 50 understood that my invention is not limited thereto, but that the sucker elements may take any other suitable form, such as flat, or may take a dome form or some variant thereof.

It is to be understood that as to the state-

ments hereinbefore made and with reference to the hereinafter described devices that the lubricating, viscous or other material for wetting the sucker surfaces is assumed to be of similar character in the various cases mentioned. And it is to be further understood that the amount of separation between the sucker elements illustrated in the drawings is not limitative of my invention, but merely illustrative.

By preference I make the sucker elements in the form of cones, one cone fitting accurately over the other; and in order to keep the surfaces apart by a very small distance and at the same time to have a control over that distance, I find it desirable to cut off the apex of the lower or fixed cone and correspondingly flatten the inner apex of the upper or moving cone. I tap a screw having a very fine thread axially through the substance of the lower cone and cause its end to impinge on the flattened surface at the inner apex of the movable cone. By turning the screw I vary the distance between the cone surfaces lifting the upper one slightly 80 from its seating on the lower one. It will be evident that the surfaces will be separated by a distance which is equal to the axial distance through which the screw moves multiplied by the sine of half the angle of the cone. By varying the angle at the apex of the cones I can vary the distance by which the surfaces are separated for a given lift of the screw.

The level of the lubricating material may 85 be sufficiently high to immerse the lower cone but it is enough if the level of its surface is about half way up the height of the lower cone. In the latter case if the lubricating material be oil there is no leakage 90 around the screw, nevertheless, the cone surfaces are sufficiently lubricated because the distance by which they are separated is not great enough to prevent the liquid covering the whole area of the cone surface. That 100 part above the level of the oil being fully lubricated by the action of surface tension or capillarity.

In the foregoing description the cones have been assumed to be placed with the 105 apex uppermost. I can however dispose the cones the other way up. In this form of my invention the lower cone is fixed into the containing vessel by a screw. The screw is rigidly fixed in the bottom of the contain-

ing vessel and has a very fine pitch. The apex of the cone is flattened as before mentioned and is drilled and tapped to fit the before mentioned screw. The movable sucker is truncated and drops within the lower cone in such manner that the before mentioned screw impinges upon the flat truncated end. In this arrangement the distance by which the surfaces are separated is controlled by turning the lower sucker around on the fixed screw.

The lid of the containing vessel may be attached by suitable rods or pins to the lower cone so that on giving an angular motion to the lid this is communicated to the lower sucker. An indicating scale may of course be provided.

In all cases the arrangement is such that the true start delaying principle embodied in my said prior patent is not interfered with, suction is still relied upon to give the time lag, but the relation between force and time is changed at will.

Since the action of two suckers whether cone shaped or flat as a start delaying device depends upon the viscosity of the liquid used to lubricate them it is necessary where extreme accuracy is required to provide the means of compensating for changes in temperature. A lessened viscosity may be met by a smaller clearance between the sucker faces. If therefore we reduce the distance between these faces by the correct amount as the temperature rises we obtain the final control required. This is done automatically by inserting a rod of steel or other convenient metal up the center of the regulating screw. The axis of the regulating screw and that of the rod coincide. The screw itself is made of brass or of some metal having a much higher coefficient of expansion than the rod. The rod is free to slide within the screw but is rigidly attached to the screw at its lower extremity. Its upper extremity impinges upon and supports the upper cone. On an increase of temperature taking place the brass screw expands to a greater degree than the rod and in consequence the suckers are allowed to approach one another. Suitable lengths of screw and rod must be of course selected. At the same time the increase of temperature lowers the viscosity of the lubricating liquid and if suitable metals be selected for the screw and rod and a suitable liquid having a small change in viscosity for a given temperature be selected for the lubricant a true compensation is obtained over a considerable range of temperature. In calibrating the instrument for accurate work the effect of surface tension must be taken into account. This may be measured by floating a flat sucker on the surface of the lubricating liquid proposed to be used in the start delaying device. The weight required to separate the sucker from

the surface of the liquid is a measure of the surface tension. When calibrating this weight so ascertained is added to the weight of the upper sucker and its connecting rod. Calibration is then carried out with the suckers chemically clean. As soon as the necessary readings for calibrating the instrument have been taken the weight representing the force of surface tension is removed. When the lubricating liquid is added and an overload applied to the start delaying device slightly in excess of the calibration setting it will be found that after the lapse of a long period of time the start delaying device will yield to the over- load.

Figs. 1 and 2 show the device in elevation partly in section. A is the containing vessel, B the lower cone and C the upper cone. Similar letters denote similar parts in the two figures. D is a rod fixed to the upper cone and is provided for articulating the upper sucker to the appliance which is to be prevented from moving until a period of time has elapsed, such appliance being a circuit breaker tripping member, or any other member whose start is to be delayed. E is the fine threaded screw and F the rod made of a metal having a lower coefficient of expansion than E. In Fig. 1 hand control for determining the separation of the cone faces B and C is effected by turning the disk G which is locked on to E by means of the nut J. In Fig. 2 the same control is effected by rotating the cap H which through the pins K, K rotates the lower sucker B on the fine threaded screw E and so changes the clearance between the faces of the cones B and C. The screw E is locked to the containing vessel by the nut J. In this figure pins L, M are shown to limit the movement to one turn upon the screw. Similar pins are usually provided in G and A Fig. 1 but they are not shown in this figure. In Fig. 1 the escape of air is provided for by the ball valve N.

I have indicated in the drawings by dot and dash line levels for the liquid or viscous or other material coöperating with the sucker element surfaces. It is to be understood however that these levels may be other than indicated, so long as the material is caused to spread over the sucker element surfaces.

It is to be understood that although the figures show no means for locking the disk G in Fig. 1, nor any means of locking the cap H in Fig. 2, yet when the right distance between the sucker faces in either model has been found to suit a particular case, then the disk or cap as the case may be can be locked by a screw or pin. In this case the hand control may be described as a factory adjustment to obtain a given time for a given pull upon the rod D. Alternately the user

may be permitted to rotate G or H and so vary the time with a given pull on the rod D.

What I claim is:

1. In a sucker time element device, the combination with the sucker elements, of means holding said sucker elements apart.

2. In a sucker time element device, the combination with the sucker elements, of means for holding said sucker elements apart, and means for adjusting the separation of said elements.

3. In a sucker time element device, the combination with the sucker elements, of means for varying the distance of separation of said elements with changes of temperature.

4. In a sucker time element device, the combination with the sucker elements, of means having different rates of expansion with temperature changes determining the separation of said elements.

5. In a sucker time element device, the combination with coöperating concave and convex sucker elements, of means for holding said sucker elements normally slightly separated.

6. In a sucker time element device, the combination with coöperating conical sucker elements, of means for holding said sucker elements normally slightly separated.

7. In a sucker time element device, the combination with coöperating conical sucker elements, of means for adjusting the normal distance between said elements.

8. In a sucker time element device, the combination with the sucker elements, of means for determining the normal relative positions of said elements in the direction of relative movement of said members when separated by an applied force.

9. In a sucker time element device, the combination with the sucker elements, of means for decreasing the normal separation of said elements with increase of temperature.

10. In a sucker time element device, the combination with the sucker elements, of members having different temperature coefficients of expansion secured to each other at one end and engaging said sucker elements at their other ends.

11. In a sucker time element device, the combination with the sucker elements, of a tube engaging one of said sucker elements, and a member within said tube engaging another sucker element, said member and tube determining the normal relative positions of said sucker elements.

12. In a sucker time element device, the combination with the sucker elements, of a tube engaging one of said sucker elements, and a member within said tube engaging another sucker element, said tube and member determining the normal relative positions of said sucker elements, said tube and said member having different temperature coefficients of expansion.

13. A time element device comprising sucker elements having coöperating concave and convex surfaces.

14. A time element device comprising sucker elements having coöperating concave and convex conical surfaces.

In testimony whereof I have hereunto affixed my signature in the presence of the two subscribing witnesses.

JOHN G. STATTER.
